(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design; and,

FIG. 2 is a second image thereof.

The outermost broken lines in the figures show a display screen or portion thereof, and form no part of the claimed design. The other broken lines in the figures show portions of the animated graphical user interface that form no part of the claimed design.

1 Claim, 2 Drawing Sheets

FIG. 2

UNITED STATES PATENT AND TRADEMARK OFFICE
CERTIFICATE OF CORRECTION

PATENT NO. : D776,696 S
APPLICATION NO. : 29/534834
DATED : January 17, 2017
INVENTOR(S) : Kyle Riedel

Page 1 of 1

It is certified that error appears in the above-identified patent and that said Letters Patent is hereby corrected as shown below:

On the Title Page

In the DESCRIPTION section, after the last paragraph, insert the following paragraph:

--The appearance of the animated images transitions between the images shown in Figures 1 and 2. The process or period in which one image transitions to another forms no part of the claimed design.--.

Signed and Sealed this
Eleventh Day of April, 2017

Michelle K. Lee
Director of the United States Patent and Trademark Office
